(57) **CLAIM**

The ornamental design for an stub out support as shown and described.

DESCRIPTION

FIG. 1 is a top elevation view of the stub out support; FIG. 2 is a side elevation view of the stub out support of FIG. 1; FIG. 3 is a top elevation view of an alternative stub out support; and, FIG. 4 is a side elevation view of the alternative stub out support of FIG. 3. The broken lines on the stub out support represent unclaimed subject matter and form no part of the claimed design.

1 Claim, 2 Drawing Sheets

FIG. 1

FIG. 2

FIG. 3

FIG. 4
